DISPENSER FOR STICKLIKE ARTICLES

James C. Waldo, Toledo, Ohio

Application January 21, 1946, Serial No. 642,575

3 Claims. (Cl. 312—73)

1

This invention relates to a container magazine from which elements may be withdrawn one-at-a-time, with the succession of such elements automatically located conveniently for maintenance of the withdrawal in sequence.

This invention has utility when incorporated in a supply chamber for toothpicks of the small splint or wood type disposed in parallel relation in a hopper or chute toward a downward crevice having a back clearance medial region to expose at least one of the toothpicks transversely a sufficient extent for finger grasping at such mid-point region of the lowermost toothpick. Free falling of the bottom or valve-closure-providing toothpick is due to yield clearance in the chute or way approach to the region of withdrawal. However, at the region of withdrawal the yield is effective in such close proximity to the discharge crevice therefrom, that the final toothpick is thereby lodged. The angle of repose of the overburden toothpicks is not such as to thrust this final element clear of the chute, but it is such that as the final or bottommost toothpick is pulled out, its place is at once taken by a single toothpick lodging in its stead. The yield-holding of the toothpick at its regions on opposite sides of the mid-point clearance, where it is grasped for removal, is sufficiently strong that the lodged pick so remains, but sufficiently weak, that upon finger grasping at the midpoint, there is no bending or breaking of the slender toothpick as removed.

Referring to the drawings:

Fig. 1 is a side elevation, with parts broken away, of an embodiment of the invention for dispensing toothpicks;

Fig. 2 is a plan view of one of the pedestals, with a portion of the base therefor;

Fig. 3 is a perspective view of the removable container or central portion of the unit of Fig. 1, oriented to charge receiving position, and

Fig. 4 is a partial section and end elevation from the left of Fig. 1, the section being on the line IV—IV.

An embodiment of the invention comprises a base 1. Spaced apart and rising therefrom is a pair of pedestals 2, 3, of complementary right and left similar configuration. When constructing the item of plastic or other moldable material, the pedestals 2, 3, may be in one piece with the base 1, with opposing parallel faces 4 rising from the base 1. The remote or arc sides of the respective pedestals 2, 3, have rising from the base 1 flutings 5, 6, in parallel with the outer edges of the fluting ways slightly overhung. Accordingly, these

provide retaining seats for stacks of disk-shaped items, such as mints, chewing gum, digestion promotion tablets, and the like. The overhang region is sufficient to retain the tablet stack with the pedestal. The clearance between the overhangs of a fluting is ample to permit one to insert a finger tip and lift out one or more tablets, as desired. The lift may be straight up out of the top at a port 7.

In the build-up herein shown as a two-element structure, between the pair of pedestals 2, 3, may be inserted a magazine or article dispensing receiver or container comprising arc-shaped top 8 symmetrical with the rounded summits of the pedestals 2, 3, in giving a slightly stream-lined general configuration to the unit. Continuation of the top wall 8 is in a vertical front side 9 to a straight lower edge 10 having a medial arc recess 11. Depending from the rear side of the top 8 and in continuity therewith but tapering or slanting forwardly is a companion wall 12 having its lower edge 13 parallel to but slightly spaced from the edge 10 of the front wall or side 9. A clearance notch or arc recess 14 centrally of the edge 13 is in register with the recess 11 of the edge 10. Flush with the edges of the depending side walls 9, 12, the arc top 8 has end semicircular disk portions 15. From the top downward, the outer face of each end 15 has a dovetail or undercut rib 16 adapted to register with complementary seat 17 of sufficient downward extent from the arc top pedestals for the top 8 to register smoothly therewith in the unit assembly.

It is to be noted that in the preferred construction, the relatively longer chute side 12 is in itself slightly resilient or yieldable. The purpose thereof is that it may maintain a spacing or crevice way 18 of such transverse dimension as just to retain an object, as a toothpick 19 from falling, but sufficiently local in this terminal engagement to allow the lowermost toothpick of the stack or charge thereof as in parallel in chamber 20 of the second element 8, 9, 12, of the unit, to be across the finger way region 11, 14.

In such location, the bottom-most toothpick 19 may be engaged by one's fingers, to be readily released thru the port or way 18. As this single toothpick 19 is withdrawn, automatically the place it vacated is taken by a follower toothpick in the stack. There is thus maintained for dispensing service a short medial exposed toothpick region at the notches 11, 14, for the next toothpick dispensing service.

While the character of the wall 12, say as to

its plastic nature, may retain the efficient resilient response for holding the article dispensing one-at-a-time and that without hazard even to the frail structure of a wooden toothpick medially grasped, occasion may arise for prolonging the efficient life performance of the item, say at a cashier's desk in a restaurant, or other general service place frequented by patrons. Somewhat back from the edge 13, and equal distances from the edge 13, may be a pair of ports 21 inclined upward and outward thru the wall 12, to have thrust therethru parallel legs 22 of a U-strip having an outside connecting portion 23. Of perfumed, breath treating, mouth care promotion properties in a fiber, paper or plastic 22, there is thus achieved final holding for release of a toothpick 19, yieldably wiped on such release with disinfectant, antiseptic, germicidal, pleasant-odor-imparting treatment. Maintenance of the desired efficiency of impregnation is thru reversal of the insert 22, 23, and replacement.

The removable insert 22, 23, may be impregnated thruout. However, for effective performance there should be impregnation 24 adjacent the crevice between the edges 11, 13, upon the opposite sides of the finger grip clearance 11, 14. In this location, as the toothpick 19 is withdrawn, the end portions thereof are each given the treatment as fresh for forthwith introduction of either end of the toothpick into the user's mouth.

Location of the unit at the cashier's desk, as a cashier's aid, renders the service for teeth attention thru the supply of a toothpick, but more extended service is as readily available thru the supply of tablets 25 of various kinds in the several seats 5, 6, located upon the outer sides of the pedestals 2, 3, opposite from the seats 17 locating the magazine having the chamber 20 for toothpick supply.

Upon occasion for restocking the chamber 20 with toothpicks, the intermediate element 8, 9, 12, is lifted out, turned to direct the crevice portion upwardly. This exposes the triangular open ends above the disk portions 15, so that the toothpicks may be piled in, even to extend upward into the now-inverted chute region. The toothpicks as so placed, should not have the ends extend out. As so charged, the receptacle may be oriented and located for its seat portions 16 to register with the pedestal seats 17.

The assembly is of arch suggestiveness with a rectangular clearway between the pedestals below the chute discharge crevice. The right-and-left contour of the pedestals on the base 1, 55 impart general bilateral symmetry to the unit as carrying the bridge of the container therebetween.

The flow or flex characteristic for the legs 22 of the insert provides the slight yieldable holding for the lowermost toothpick, especially in the event 60

the resilient life of the chute side 12 be spent or not initially appropriate.

What is claimed and it is desired to secure by Letters Patent is:

- 5 1. A dispenser unit comprising a platform-providing base, within the bounds of said base a pair of upright pedestals having opposing guide-providing faces forming seats spaced from the base, and an open-ended chute-providing container 10 having seat portions complementary to the seats of the pedestals and adapted to ride along the guide faces to bring the top of the container into flush relation with the tops of the pedestals, said container chute having a discharge slot at the 15 bottom thereof opening downwardly between the pedestals.
2. A dispenser unit comprising a base, spaced inward from the bounds of the base there being a pair of pedestals having opposing parallel faces 20 with inwardly extending guide seats remote from the base and extending theretoward, the tops of the pedestals in their extent away from the seats being spherically convex, and a container with a semi-cylindrical top having complementary end 25 seats registering with the pedestal seats in bringing the container top in to flush relation with the tops of the pedestals, said container having a pair of converging side walls extending downwardly from its semi-cylindrical top to form a chute with a dispensing slot at the bottom thereof.
3. A dispenser unit including a container having a pair of opposing downwardly converging chute walls ending in parallel spaced portions providing a slot outlet, there being parallel port 35 means in one of the walls spaced from the outlet, and a treatment carrying U-shaped element having resiliency in the legs thereof, said legs of the element being inserted through the port means with the free ends of the legs extending in outlet 40 restricting position whereby articles to be dispensed by removal from the outlet have wiping treatment by the element.
